DIPPED BALLOON

Bert L. Morr, Chester A. Butts, and Edgar H. Walters, Ashland, Ohio, assignors to Ashland Rubber Products Corporation, a corporation of Ohio

Application October 12, 1949, Serial No. 121,014

1 Claim. (Cl. 46—87)

1

This invention relates to dipped elastic walled inflatable objects, particularly toys having generally rotund bodies and spaced supporting legs. Toys simulating animals are at the moment foremost in contemplation.

The conventional method is to provide a convex form with spaced leg cores, that when dipped produces an initially convex body with leg extensions which when inflated to the point of shape sustaining tension, becomes uniformly stretched circumferentially so that the leg extensions stand out divergently in an unlikeness manner.

One of the objects of the present invention is to provide a dipped balloon that in uninflated state is angularly re-entrant along its opposite side and flat along the bottom, with the leg extensions emanating from the flat portion, the re-entrant angular portions providing fullness in the body above the flat bottom portion, which becomes reversely bulged under incipient inflation to form a convex body without stretching, so that under the slight additional amount of inflation necessary to give the balloon the degree of tension essential to sustain its shape, the flat bottom portion which is proportionately stretched, assumes the shape of an arc, of which the original width of the flat portion is the chord, so that the ends of said arc are not spread beyond their original distance apart, causing the leg extensions to remain substantially unspread and parallel.

Another object of the invention is the provision of a balloon having the characteristics imparted by the form.

Other objects of the invention will appear as the following description of an illustrative embodiment thereof proceeds.

In the drawings which accompany the following specification, and throughout the figures of which the same reference characters have been used to denote identical parts:

Figure 1 is a side elevation of a form or mold embodying the principles of the invention;

Figure 2 is a cross-section taken along the line 2—2 of Figure 1;

Figure 3 is a diagrammatic cross-section showing the balloon in full lines in uninflated shape; in dash lines, distended by inflation but not stretched, and in dotted lines, inflated to normal shape sustaining tension.

Figure 4 is a side elevation of the balloon when inflated.

Referring now in detail to the figures, the numeral 1 represents a mold or form which has

2

the profile of a four legged animal, minus the head. The head is made on a separate form, with which the present invention is not concerned.

5 The form 1 comprises a longitudinal horizontal base 2 and a vertical longitudinal fin 3, which meets the base in a medial longitudinal plane. The leg portions 4 extend substantially perpendicular from the lower face of the flat base, spaced apart transversely. The form has tail and neck extensions, but these are mere incidents to the particular object to be simulated.

The form is used by dipping it in, or drawing it through a latex emulsion or other rubber-like liquid so that a film of the liquid collects on the form up to the neckline 5. That part of the form above the neckline merely provides for its attachment to a conveyor and need not be further described. The latex film deposited on 15 the form is, after suitable coagulation, stripped from the form and becomes the body component of the balloon which, associated with a head component from another form becomes, when suitably inflated, the animal 6 shown in Figure 20 4. In this example the balloon is inflated through a hole in the tail, closed by a plug 7.

The fin 3 and base 2 of the form make re-entrant, that is, concave dihedral angles *a* and *b*, extending substantially throughout the length 25 of the body of the form, there being fillets in the apices to facilitate stripping the elastic skin which constitutes the balloon, from the form.

Figure 3, in full lines, shows the cross-sectional shape of the balloon after having been stripped 30 from the form, but prior to inflation, the shape of the form being retained. It will be noted that there is a vertical fold 8, corresponding to the fin 3, and opposite lateral folds 9 and 10 corresponding to the base 2 of the form, the lower limbs of the lateral folds forming a continuous flat bottom face 11 from which the leg portions extend, laterally spaced apart and substantially parallel to each other.

The lines *v* *w* and *x* *y* represent planes that touch the end of the vertical fold 8 and the ends of the respective lateral folds 9 and 10. The first stage of inflation is to fill the balloon to a point just short of stretching it. This causes the sides of the folds 8 and 9 which form the re-entrant dihedral angles *a* and *b* to reverse their position with respect to the said planes and to stand out on the opposite sides of said planes in a convex manner, as shown in the dash lines in Figure 3. This degree of inflation has

had no effect upon the face 11, which is still flat.

Now in its distended but unstretched condition the balloon is still limp, so as to be incapable of self support. It must be further inflated to put it under enough tension to sustain its shape. It is not contemplated that articles of this nature shall be inflated to a substantially greater degree than is required to make them sustain their shape.

Under tensioning pressure from within, the cross-section of the body becomes circular, as shown in dot and dash lines in Figure 3, since the pressure of the gas is equal in all directions and the envelope is uniformly elastic. The convexed dihedrals round out into a continuous circular curvature defining the sides and back of the animal. The flat under face 11 also rounds out into an arc of the same curvature as the sides of the body, the original width of the flat under face 11 being a chord of that arc. Since the length of an arc is greater than its chord, the amount of stretching that the chord undergoes in becoming the arc is taken up in the arc without the points 13 and 14 at the ends of the chord moving laterally. The points 13 and 14 represent the outer points of juncture of the leg portions with the flat face 11.

Likewise, with respect to the points 15 and 16, which represent the inner points of juncture of the leg portions with the flat face 11, the part 17 of said flat face which lies between these points stretches to become the arc 18 without causing lateral displacement of the points 15 and 16. Therefore, the relative positions of the leg portions remain substantially constant as the chord changes to the arc, and they remain substantially parallel and substantially the same lateral distance apart as they were before the balloon was put under tension.

While it is true that the inner sides of the leg portions become shorter as the flat portion 11 assumes an arcuate form, which might be expected to tilt the leg portions divergently, this tendency is offset by the fact that the leg portions also stretch, increasing in girth along their lines of juncture with the body portion, relieving to a great extent the forces engendered by the unequal lengths of the inner and outer sides of the leg portions.

In the case of a convex form with leg extensions, after the first step of inflating to the point just short of tension has been accomplished, the entire circumference is already arcuate, so that

the second step of stretching to the point of producing tension, stretches the circumference including the arc between the leg portions, spreading the leg portions divergently. In the present invention, the corresponding first step results in giving the sides and back a convex contour, but the under face 11 to which the leg portions are jointed, remains flat. The second step, therefore, does not change the distance between the leg portions, but stretches the chord between said legs into an arc of equal transverse amplitude.

The result in the properly inflated balloon is a more lifelike appearance, since the legs are spaced apart a definite distance determined by the form, and are substantially parallel instead of divergent, giving the base of support a square appearance, and imparting unusual stability to the animal.

The employment of a form embodying the principles of this invention also reduces the size of the form and the weight of the same.

While we have in the above description disclosed what we believe to be a practical embodiment of the invention, it will be understood by those skilled in the art that the specific details of construction and the arrangement of parts as shown, are by way of illustration and not to be construed as limiting the scope of the invention.

What we claim as our invention is:

Dipped balloon comprising an inflatable elongated bag simulating a four-legged animal, which in its uninflated repose state has a longitudinal upright fold and opposite lateral folds, said upright fold making reentrant dihedral angles with the respective upper sides of said lateral folds, the lower sides of said lateral folds lying in a common plane substantially perpendicular to said upright fold forming a flat base, and parallel leg extensions emanating from said base.
